ELECTRON TUBE MOUNT ASSEMBLY
MECHANISMKenneth C. Rupert, Mill Hall, Pa., assignor to Sylvania
Electric Products Inc., a corporation of Massachusetts

Filed Feb. 25, 1959, Ser. No. 795,456

8 Claims. (Cl. 153—2)

This invention relates to the manufacture of the mount portion of an electron tube and in particular relates to assembling apparatus for such mount.

Some types of electron tubes employ a pair of spaced insulators, such as mica, between which are located electrodes of the tube. These electrodes may include many elements, but for the purposes of clarification of this invention, a simple type of electron tube is selected for assembly of parts, as a filamentary cathode type duodiode employing a pair of spaced hollow anodes with filamentary cathodes, one in each anode, the filaments of the cathodes being connected in series. Such a tube may be used as a full wave rectifier.

It is an object of this invention to provide an apparatus which shall facilitate assembly of parts of an electron tube.

It is a more specific object of the invention to provide a mechanism which shall facilitate the association of insulating supports with lug provided elements of an electron tube mount and which shall bend these lugs against the insulating supports.

It is also an object of the invention to provide in a mount assembly device, a mechanism which shall in one continuous operation of the machine variously bend a multiplicity of lugs.

These and other objects will become apparent after consideration of the following specification when taken in conjunction with the accompanying drawings in which:

Fig. 1 is a side elevation of the machine showing parts in a normal inoperative position.

Fig. 2 is a top plan view of the machine.

Fig. 3 is a section of the machine on the broken line 3—3 of Fig. 2, showing the tools in partially shifted position, the mount being shown in dotted line, and parts being broken away.

Fig. 4 is a section similar to Fig. 3 showing the final position of parts after lug bending operations have been completed.

Fig. 5 is a section on the line 5—5 of Fig. 1 showing lug bending tools in a retracted position.

Fig. 6 is a similar section with the same bending tools in an advanced position.

Fig. 7 is an enlarged view showing lug bending tools operating on lugs beneath the lower spacer element.

Fig. 8 is a section through lug bending tools, a slide supporting the same and a slide box, taken on the line 8—8 of Fig. 5.

Fig. 9 is a plan view of a nest to seat parts of the electron tube mount.

Fig. 10 is a section on the line 10—10 of Fig. 4 showing how the anode portion of a mount is gauged into position on the machine.

Fig. 11 is a section on the line 11—11 of Fig. 1.

Fig. 12 is a vertical section on the broken line 12—12 of Fig. 4 and

Fig. 13 is an exploded view of a mount prior to lug bending.

Referring to the drawings in greater detail, at 20 is

2

a rectangular table top adapted to be mounted on frame legs, not shown. At the forward end of the table is a spacer block 22 set into a recess in the table and having raised end walls 24 to form a channel 26 between the walls. Mounted atop the walls and straddling the channel is a nest 28. A pair of long screws 30 pass freely from underneath the table, upwardly through the table and the spacer and thread into the nest to firmly bind all three parts together. The nest is provided with a

pair of parallel channels 32 formed in the upper surface thereof to allow for passage therethrough of two lug bending tool carriers 34 and 36. At the forward end of each of the parallel channels is a vertical hole 38 through the nest to allow for debris in the channel to drop out as the tools move forwardly in the channels. At right angles to the channels 32 and recessed in the top face a depth equal to the thickness of the bottom insulating spacer of the mount is a cross channel 40, the same being of a width equal to that of the bottom spacer of the mount.

Referring to the exploded view of the mount as shown in Fig. 13, it will be seen that the mount here illustrated as being operated upon by the machine consists of a bottom spacer 42 with parallel sides and rounded ends provided at each rounded end with a slot 44 centrally of

the rounded end and two slots 45 and 46 parallel with slot 44 but nearer the center of the spacer. Also there is provided in the spacer a pair of slots 48 parallel to each other but perpendicular to the slots 44 and 46. The slots 48 are adapted to accommodate the lugs 50 of a

strap 52, which lugs are to be bent over the top of the spacer, while the slots 46 are adapted to receive downwardly extending lugs 54 on webs 56 of anodes 58. The tops of the anodes carry lugs 60 on the webs 56 which pass through slots 62 in a top spacer 64 and also lugs 66 on the anodes, per se, which pass through the remaining openings 68 in the top spacer. It has been found sufficient for the purposes of holding a mount together in the assembly machine to merely bend the top lugs 60 tightly against the upper surface of the top spacer,

to bend the lower lugs 54 tightly against the bottom spacer and to bend one pair of bottom anode lugs 66, as those passing through slots 46 in the bottom spacer, loosely against the bottom of the spacer. The mechanism of the invention bends all the lugs which have been indicated should be bent. The purpose of the strap in the mount is to provide a series connection between filamentary cathodes which are to be inserted within the anodes, one leg of each filament being subsequently welded respectively to each end of the strap while the

otherwise free ends of the cathode filaments are connected to the filament leads of a stem supporting the mount.

As stated heretofore, the bottom spacer 42 is placed in the channel 40 and threaded over the lugs 50 on strap 52. This strap has a rib reinforced vertical web portion 70 adapted to be positioned in a vertical slot 72, Figs. 9 and 11, in the nest with chamfered edges 73 to facilitate insertion of the portion 70. The strap also has a horizontal web portion 74 supporting the lugs 50,

which is adapted to lie in a deeper recessed portion 76 in the nest so that the top surface of web 74 is at the general level of the floor of the channel 40 and so that the spacer 42 may properly seat in the channel. Suitable slots 78 may be provided at the sides of the channel 40 and recesses 80 adjacent the recess 76 to facilitate removal of debris about these parts.

At the rear of the nest is a top tool support 82 having feet 84 and held to the table 20 by screws 86, the support having reinforcing gussets 88. Fixed to the top portion of the wall by bolts 89 is a bearing plate 90 provided with laterally spaced vertical bearing ears 92 overlying the support 82, each provided with a vertical pivot

bearing slot 94, a pivot pin 96 being slidably and pivotally mounted in the slots. The pin is held down to the bottom of the slots 94 by a spring 98 wrapped around the pin at one end and fastened at its other end beneath the head of a bolt 100 screwed into the support 82.

Mounted on the pivot 96 is the top lug bender 102 comprising a plate with a cam follower roller 104 held in a bifurcation at its rear end and a pair of tines 106 at its forward end. A spring 108 tensioned between the rear end of tool 102 and a pin 110 screwed into the support 82 serves to hold the roller 104 against the top of a top cam 112 which will be described later. At the forward end, the lug bending tool is elevated to permit insertion into the nest, the parts of the mount which will subsequently, by operation of the described mechanism, bind them all together. To assist in the assembly of the parts, there is mounted a guide 114 on the front wall, as by bolts 116, this guide having, see Fig. 10, a vertical front flange 118 against which the webs 56 of the anodes may be brought to bear. The lateral edges of the flange provide bearing for the inside faces of the anodes.

When the portions of the mount illustrated in Fig. 13 have been assembled on the nest assisted by the flange 118, the cam 112 is driven upward moving the lug bending tines from the normal rest position shown in Fig. 1 to the position of Fig. 3. Slightly further movement causes the tines 106 to engage the lugs 60 to bend them to the left in Figures 3 and 4. Were not the spring 98 and slots 94 provided, further movement of the tines would cause them to dig into the spacer, usually of mica, thereby damaging the mount. However, because of the provision of the shifting pivot 96, the tool merely has a wiping motion across the bent lugs as it moves toward the position of Fig. 4. The lugs are thus bent down tightly against the mica or other spacer without damage thereto.

The tools and associated mechanism for bending the lugs about the lower spacer resting in the nest will not be described.

Fastened to the table 20, as by screws 120 is a slide channel or housing 122, Fig. 9, covered with a cover plate 124 held to the side walls of the channel by bolts 126. Slidable within the channel is a slide 128 of a width to fit the lateral dimension of the channel. The slide has a longitudinal central rib 130 extending upwardly to provide seats at the sides of the rib for the lug bending tool carriers 34 and 36, whose tools bend lugs extending below the lower spacer 42. These carriers are loosely pivoted on a horizontal pivot pin 132, Fig. 3, passing transversely through the rib 130 near the front end of the slide. The slide 128, Figs. 5 and 6, at its rear end is provided with a bifurcation 134 carrying a cam follower roller 136 on a pin held by a screw 137 engaged by a second and lower cam 138, as will be described, to advance the slide. The slide is retracted against the action of cam 138 by a pair of springs 140 tensioned between projections 142 extending rearwardly and then upward from an anchor plate 143 fastened to the top of the cover and a pair of dowels 144, these dowels passing freely through slots 145 in the cover plate 124 and being fixedly mounted in the slide 128 forwardly of the pivot pin 132. These dowels also serve as vertical pivots for carriers 146 and 148 for the tools which engage the pair of lugs 50 extending above the lower spacer 42. The tool carriers rest on the central rib 130 of the slide. To pivot the carriers 146 and 148, their back ends are bevelled as indicated at 150 in Figs. 5 and 6 and the cover plate 124 has inserted in the underside thereof a wedge block 152, held to the plate by a bolt 154 passing through the cover plate and threaded into the block. To restore the tool carriers 146 and 148 to their normal position when the slide is retracted, there is provided a compression spring 156 forwardly of the pivotal dowels 144, the spring being seated in recesses of the carriers and surrounding pins 160 mounted in the recesses.

The forward ends of the carriers are formed into tools which are undercut, see Figs. 3, 5 and 6, so that the vertical walls 162 of the undercut when projected forward opposite the lugs 50 on the strap may engage the same when the carriers are pivoted, in order to bend the lugs down on top of the mica. The tools are projected through a rectangular opening 164 in wall 82 which opening has rounded corners and underneath a bridge 166 held to the nest by bolts 168, to prevent upward movement of the tools relative to the nest and spacer therewithin. Thus this tool resists upward thrust of the tools operating on lugs extending beneath the same mica spacer. The carriers 34 and 36 for the tools beneath the spacer are pivoted so that their tool ends move upwardly just prior to the complete projection of the slide by reason of a sharp rise 172 on each carrier near the rear end thereof leading to a flat or land 174. The rise on the end of each carrier engages the rear edge of a longitudinal rib 176 extending along each side of the cover plate and within the channel, the rise thereby causing a depression of the rear end of the carrier as the slide moves forward. This is to cause the lugs 54 which have previously been bent by a thrust action of tools borne by the carriers to be bent tightly and upwardly against the lower spacer. The other lugs passing downwardly through the spacer are not so bent. In fact only two additional lugs, those passing through the slots 46 in the lower spacer, are bent, but not tightly, against the spacer. To ensure restoration of the carriers 34 and 36 to their original positions, a sharp rise 178 is provided on each of the carriers adjacent the front edges of the cover borne ribs 176 so that as the slide is withdrawn, the forward ends of the carriers will be depressed.

Each carrier at its forward end has a dual tool formation indicated as 180 and 182, see Fig. 7, offset from each other laterally and perpendicularly. The tools 180 are in line with the lugs 54 below the spacer and are nearer the edges of the spacer than the tools 182. The tools 182 are adapted to engage the lugs on the anode which extend through the slots 46 in the spacer and are hollowed out, as indicated at 183 to miss the lugs extending through the slots 45. The forward edges of the tools engage the lugs and bend them as the carriers 34 and 36 are advanced. The tools 182 are below the level of the tools 180 so that when the carriers 34 and 36 are pivoted about the horizontal pin 132 by engagement of the risers 172 with the rear edges of the ribs 176, the tools 180 will bend the lugs 54 tightly against the spacer, while the other lugs will be bent but slightly more than by the pushing action of the tools 182.

As stated heretofore, the upper tool or top lug bender 102 and the slide 128 are operated by the cams 112 and 138. These cams are bolted onto a vertical cam slide bar 180 riding in a pair of vertical guides 184 fastened to a cam slide bar support or bracket 185 comprised of a rectangular plate 186 and two truncated triangular side members 187. The bracket 185 is bolted to the table 20 and a large opening 190 is provided in the table for proper passage therethrough of the slide bar with its cams.

The cam slide bar is operated by a fluid motor 192 under operator control, the cylinder of which is provided with inlet and outlet openings, and heads 196. Tie rods 198 for tightening the heads against the cylinder are provided. The upper head 196 is bolted to a motor mounting plate 200 in turn fastened to a pair of cylindrical spacers 202 in the upper ends of each of which is bottomed a headless bolt 203 with protruding end which can be screwed into the bottom of the table until the spacer butts tightly against the bottom of the table. An air cylinder connector 204 and yoke 206 connects the bottom of the slide with the piston rod 206 of the motor.

In the operation of the cams on the slide, the top lug bender not only serves to bend the lugs downwardly but assists the tie strap lug bending tools above the lower spacer in holding the mount in place while the lowermost

set of bending tools is thrusting upwardly against the anodes and the bottom spacer.

What is claimed as new is:

1. An electron tube mount assembling mechanism comprising a base, a horizontal nest mounted on said base, means in the top of said nest to position a tie strap, said strap having a vertical web and upwardly facing lugs near opposite ends of the straps with the planes of the lugs parallel to each other and perpendicular to the plane of the vertical web, other means on top of said nest to support an insulating spacer with the lugs traversing holes in the spacer, a first support fixedly mounted on said base, guide means fixed on said first support to position a pair of anodes with lugs at their bottoms traversing other holes in said spacer, lugs at the tops of said anodes, a second spacer mounted atop said anodes with holes in said second spacer traversed by said top lugs on the anodes, a lug engaging tool pivotally and slidably mounted on said first support, other bending tools slidably mounted in said nest to engage and bend the lugs on the strap and on the lower ends of the anodes, and means to operate all of the tools.

2. In an electron tube mount assembling mechanism, means to support an assembly of a lower insulating wafer, an upper insulating wafer and an anode structure between the wafers, said anode structure having lugs at the top edges extending through openings in the top spacer, an upright mounted on the support, a vertically elongated pivot bearing at the upper end of the upright, a lever having a pivot intermediate its length pivoted in said elongated bearing, a spring tending to hold the pivot down against the bottom of the elongated bearing, a lug bending element at the forward end of the lever, and lever raising mechanism at the rear end of the lever, whereby the lug bending element first engages the lugs to bend the same against the top surface of the wafer and then wipes across the lugs to firmly press them down against the wafer without injury to the wafer.

3. In an electron tube mount assembling mechanism, a fixed nest having a channel adapted to support a wafer and a deeper recessed portion adapted to support a strap, said strap having a pair of spaced upstanding lugs, said wafer threaded over the lugs and resting in the channel, and an anode structure above the wafer with lugs threaded downwardly through the wafer, lug bending sets of tools movable in the nest transversely of the strap, one set of tools engaging lugs in its path of travel and below the wafer to bend the lugs, another set of tools engaging the lugs above the wafer to bend them, and means for moving the tools of the second set toward each other after they straddle the upstanding lugs.

4. In an electron tube mount assembling mechanism, a fixed nest adapted to support a strap having a pair of spaced upstanding lugs, a wafer threaded over the lugs, and an anode structure above the wafer with lugs threaded downwardly through the wafer, lug bending sets of tools movable in the nest transversely of the strap, one set of tools engaging lugs in its path of travel and below the wafer to bend the lugs, another set of tools engaging the lugs above the wafer to bend them, means for moving the tools of the second set toward each other after they straddle the upstanding lugs, a fixed slide movable in the box toward and from the nest, said first set of tools being mounted on the slide, fixed vertical pivots on the slide, said second set of tools being pivoted on said pivots and means on the box engageable with the rear ends of the tools of said second set to pivot the lug bending tool ends toward each other when the slide is advanced toward the nest.

5. In an electron tube mount assembling mechanism, a fixed nest adapted to support a strap having a pair of spaced upstanding lugs, a wafer threaded over the lugs, and an anode structure above the wafer with lugs threaded downwardly through the wafer, lug bending sets of tools movable in the nest transversely of the strap, one set of tools engaging lugs in its path of travel and below the

wafer to bend the lugs, another set of tools engaging the lugs above the wafer to bend them, means for moving the tools of the second set toward each other after they straddle the upstanding lugs, a fixed slide box, a slide movable in the box toward and from the nest, said first set of tools being mounted on the slide, fixed vertical pivots on the slide, said second set of tools being pivoted on said pivots, means on the box engageable with the rear ends of the tools of said second set to pivot the lug bending tool ends toward each other when the slide is advanced toward the nest, said slide also mounting a horizontal pivot with the first set of tools pivoted on the horizontal pivot, said first set of tools having elevated portions on the top faces thereof at areas forward and rear of the horizontal pivot, said areas being engageable with the forward and rear edges of the box to tilt the lug engaging ends of the first set of tools away from the spacer prior to advance movement of the slide toward the nest, and to tilt the same ends toward the spacer upon full movement of the slide toward the nest.

6. In an electron tube mount assembling mechanism, a fixed nest adapted to support an insulating spacer mounting anodes, each anode having at least two lugs threading the spacer and extending therebelow, a fixed box, a slide movable therethrough and movable toward and from the nest, said slide having tools movable over the top of the spacer, and tools movable under the spacer to press against and bend the lugs up toward the spacer, the said two lugs being misaligned laterally of the direction of movement of the slide and the tools on the slide being misaligned in a like manner to engage the lugs in the movement of the slide toward the nest, the lug engaging ends of the tools on the slide being vertically displaced as well as laterally displaced whereby one tool will bend the lug it engages to a greater angle than the other, and means to elevate the lug engaging ends of the tools whereby one lug, at least, will be bent tight against the spacer.

7. In an electron tube mount assembling mechanism, a fixed nest adapted to support a strap with upstanding lugs and an insulating spacer threaded over the lugs, there being an anode resting on the spacer with lugs extending downwardly through the spacer, means for bending the lugs of the strap and anode toward the spacer comprising a fixed box including a cover plate, a slide through the box and movable toward and from the nest, a horizontal support on the slide, tools mounted on the horizontal support of the slide which have free ends adapted to engage the anode lugs to bend the same on advance of the slide relative to the box, vertical pins on the slide extending up through slots in the cover plate, a pair of tools mounted on the pins within the box whose forward ends are adapted to engage and bend the strap lugs, a cam on the lower face of the cover plate between the pin mounted pair of tools to pivot the pair of tools about the pins when the forward ends of the tools of the pair straddle the strap lugs, springs reacting between the box and the pins to retract the slide, and means to thrust the slide toward the nest against the action of the springs.

8. An electron tube mount assembling mechanism comprising a base plate, a nest mounted on said base plate adapted to support thereon an assembly comprised of a strap, a bottom and top insulating spacer, and an anode between the spacers, said strap having upstanding lugs which thread through the bottom spacer, the anode having bottom lugs threaded downwardly through the bottom spacer and top lugs threaded upwardly through the top spacer, a slide carrying tools movable toward and from the nest, said tools being movable above and below the bottom spacer and engageable with lugs threading the

bottom spacer to bend the same, a vertical top tool support fixed to the base plate, a top tool engageable with top lugs on the anode extending upwardly through the top spacer, said tool being pivoted in a vertically elongated bearing in the top tool support, a second vertical support fixed to the base plate, a cam slide vertically shift-

able in the second support and through the base plate, motor means supported beneath the base plate connected with the cam slide to move the same, an upper cam on the slide engageable with the rear end of the top tool to pivot the same and then shift the pivot as the tool engages the top anode lugs, a second lower cam on the cam slide to engage the rear end of the tool slide to shift the same forwardly toward the nest, spring means tensioned by the pivoting and shifting of the top tool by the top cam, and other spring means tensioned during the shifting of the slide by the lower cam, all spring

means tending to restore parts to normal tool inoperative positions when the cam slide is lowered.
